his Attorney.

UNITED STATES PATENT OFFICE.

ARTHUR J. HOWE, OF LAKESIDE, OHIO.

CASTER-WHEEL.

1,369,243.

Specification of Letters Patent. Patented Feb. 22, 1921.

Application filed August 30, 1920. Serial No. 406,919.

To all whom it may concern:

Be it known that I, ARTHUR J. HOWE, a citizen of the United States, residing at Lakewood, in the county of Cuyahoga and 5 State of Ohio, have invented a new and useful Caster-Wheel, of which the following is a specification.

This invention relates to improvements in 10 caster-wheels, and pertains more especially to a caster-wheel having a removable rim which has circumferentially extending side flanges and an elastic and compressible solid tire between said flanges.

The object of this invention is to facilitate 15 the assemblage of the component parts of a caster-wheel of the character indicated, to render the wheel simple and durable in construction, to have the hereinbefore mentioned tired rim conveniently removable 20 from the body of the wheel for renewal or repairs, and to efficiently and inexpensively hold said rim in place on said body.

With this object in view, and to attain 25 any other object hereinafter appearing, this invention consists in certain features of construction, and combinations and relative arrangements of parts, hereinafter described in this specification, pointed out in the 30 claims, and illustrated in the accompanying drawings.

In said drawings, Figure 1 is an elevation of a caster-wheel embodying my invention. Fig. 2 is a central section taken along the 35 line 2—2, Fig. 1, looking in the direction indicated by the arrow. Fig. 3 is a vertical section taken along the line 3—3, Fig. 2, looking in the direction indicated by the arrows.

Referring to said drawings, 5 indicates 40 the circular body of my improved caster-wheel. Said body is preferably of metal and has a central hole 6 for receiving an axle (not shown). Said body is provided at one end face 7 thereof with an external circumferentially extending annular flange 8, and said body is shown provided at its outer circumference, between said flange and the other end face 9 of the body and farther from said flange than from the last-mentioned face, with three cavities 10 spaced 45 preferably substantially equidistantly circumferentially of the body.

The body 5 is provided at each cavity 10 with a recess 12 which extends to said cavity 55 from the adjacent end face 9 of the body and has a sloping wall 13 which extends

from said face to said cavity. The wall 13 of each recess 12 faces in the direction of the adjacent end face 9 of the body and toward the outer circumference of the body, 60 and the cavity 10 adjacent said recess has its bottom farther from said circumference than the inner or cavity-meeting end of said wall.

The flange 8 of the body 5 forms an abutment 65 for a metal rim which preferably consists of a metal channel-member bent into substantially circular form and united together at the ends in any approved manner and comprising a base portion 15 of a cylindrical shape and also two laterally spaced outwardly projecting circumferentially extending side flanges 16 and 17. The flange 16 of the rim abuts against the inner side of the flange 8 of the body 5. The base 70 portion 15 of the rim is mounted on and surrounds and closely embraces the body 5 between the end faces 7 and 9 of the body. Said rim is provided with an annular tire 18 composed preferably of elastic and compressible material such, for instance, as rubber, and applied to the rim between the flanges 16 and 17 and fixed in place in any approved manner.

The tired rim is provided at each cavity 85 10 with a concavo-convex inwardly offset portion 19 engaging said cavity, and the inner extremity of the sloping wall 13 of the recess 12 extending to said cavity is farther 90 from the axis of the wheel than said cavity-engaging member 19 of the rim. It will be observed therefore that the tired rim is shown provided with three members 19 which project into the body 5 and are spaced substantially equidistantly circumferentially of the body. 95

As already hereinbefore indicated, the tired rim has its flange 16 abutting against the flange 8 on the body 5, and I would here remark that said rim is shown provided adjacent its other flange 17 with three radially inwardly projecting ears 20 which are spaced preferably substantially equidistantly circumferentially of the axis of the wheel and alternate with the cavities 10 in 105 the rim, and the body 5 has its end face 9, from which the recesses 12 extend to said cavities as hereinbefore indicated, overlapped by said ears. Preferably said ears are formed by parts struck or displaced 110 from the base portion 15 of the rim. The rim is shown positively secured to the body

5, preferably removably by screws extending through screw-receiving holes 21 in the ears 20 and having heads 22 counter-sunk in said ears at the outer sides of the ears. 5 Each screw (see Fig. 2) has a threaded shank 23 shown parallel with the central hole 6 in the body 5 and engaging a correspondingly threaded hole 24 in the body. As the inner or cavity-meeting extremities 10 of the sloping walls 13 are farther from the bottoms of the cavities 10 than the projecting members 19 of the rim, any force tending to displace the rim in the direction in which the hereinbefore mentioned screws 15 are withdrawable from the body 5 is opposed independently of the screws. However, the concavo-convex contour of said members 19 and the resilience of the rim at said members 19 are adequate to permit removal of the rim; by force, from the body 5, upon the removal of the aforesaid screws.

To efficiently prevent circumferential displacement of the rim independently of the body 5 is of vast importance. By my improved construction, in which the members 19 project into said body, any likely force tending to displace the rim circumferentially independently of the body is efficiently opposed, and strain by such force on 30 the aforesaid screws and on the ears 20 is prevented.

Preferably the body 5 is beveled, as at 25, between the outer ends of the recesses 12 at the outer circumference of the adjacent end 35 face 9 of the body, to facilitate the application of the rim. Preferably the recesses 12 are just wide enough to permit the projecting members 19 to move endwise therethrough during the assemblage of the parts, 40 and obviously the sloping walls 13 form guides for said members 19 during the assemblage of the parts, and the relative arrangement of the parts is such that when, during the assemblage of the parts, said 45 members 19 have come into engagement with the cavities 10 the screw-receiving holes 21 in the ears 20 shall register with the screw-holes 24 in the body.

What I claim is—

50 1. In a caster-wheel, a circular body provided at its outer circumference with several cavities spaced substantially equidistantly circumferentially of the body, and a tired metal rim surrounding the body and 55 having portions thereof projecting into said cavities.

2. In a caster-wheel, a circular body provided at its outer circumference with cavities spaced circumferentially of the body, and a 60 tired metal rim extending circumferentially of and embracing the body and having inwardly offset concavo-convex portions engaging said cavities.

65 3. In a caster-wheel, a circular body provided at its outer circumference with cavities spaced circumferentially of the body, and a 70 tired metal rim extending circumferentially of and embracing the body and having inwardly offset concavo-convex portions engaging said cavities.

ties spaced circumferentially of the body and from the end faces of the body, said body being also provided at each cavity with a recess which extends to said cavity from an end face of the body and has a sloping 75 wall which extends from said face to said cavity and faces in the direction of said face and toward the outer circumference of the body, and a tired rim extending circumferentially of and embracing the body and 80 provided at each cavity with a projecting member engaging said cavity.

4. In a caster-wheel, a circular body provided at its outer circumference with cavities spaced circumferentially of the body 85 and from the end faces of the body, said body being also provided at each cavity with a recess which extends to said cavity from an end face of the body and has a sloping wall which extends from said face to said 90 cavity and faces in the direction of said face and toward the outer circumference of the body, and a tired rim extending circumferentially of and embracing the body and provided at each cavity with a projecting member 95 engaging said cavity and extending into the cavity to a point which is farther from the outer circumference of the body than the adjacent extremity of the sloping wall of the recess extending to said cavity.

5. In a caster-wheel, a circular body provided at its outer circumference, between the end faces of the body, with cavities spaced circumferentially of the body, said body being also provided at each cavity with 100 a recess which extends to said cavity from an end face of the body and has a sloping wall which extends from said face to said cavity and faces in the direction of said face and toward the outer circumference of the body, and a tired rim extending circumferentially of and embracing the body and 105 provided at each cavity with a concavo-convex inwardly offset portion engaging said cavity.

6. In a caster-wheel, a circular body provided at its outer circumference with cavities spaced circumferentially of the body and farther from one end face than from the other end face of the body, said body being 110 also provided at each cavity with a recess which extends to said cavity from the last-mentioned face and has a sloping wall which extends from said last-mentioned face to said cavity and faces in the direction of said last-mentioned face and toward the outer circumference of the body, and a tired rim mounted on the body and provided at each cavity with a projecting member engaging said cavity, the bottom of each cavity being 115 farther from the outer circumference of the body than the adjacent extremity of the sloping wall of the recess extending to said cavity.

7. In a caster-wheel, a circular body pro- 120

vided at its outer circumference with cavities spaced circumferentially of the body and farther from one end face than from the other end face of the body, said body being 5 also provided with recesses extending to said cavities from the last-mentioned face, and a tired rim mounted on the body and provided at each cavity with a projecting member engaging said cavity, the body being beveled 10 between the aforesaid recesses at the outer circumference of the aforesaid last-mentioned face.

8. In a caster-wheel, a body provided adjacent one end face of the body with an external circumferentially extending flange, and a tired rim mounted on the body and abutting against the inner side of said flange and having ears which overlap the other end face of and are secured to the body and 20 spaced circumferentially of the axis of the wheel.

9. In a caster-wheel, a circular body provided at its outer circumference with cavities spaced circumferentially of the body 25 and farther from one end face than from the other end face of the body, and a tired rim mounted on the body and provided at each cavity with a projecting member engaging said cavity, said rim being also pro-

vided at the last-mentioned face with radially inwardly projecting ears which overlap said last-mentioned face and are secured to the body and spaced circumferentially of the axis of the wheel and alternate with the aforesaid cavities.

10. In a caster-wheel, a circular body provided at its outer circumference with cavities which are spaced circumferentially of the body and farther from one end face than from the other end face of the body 40 and being also provided at each cavity with a recess which extends to said cavity from the last-mentioned face, a tired rim mounted on the body and provided at each cavity with a member which projects into said cavity 45 and also provided at said last-mentioned face with ears which overlap said face and are spaced circumferentially of the axis of the wheel and alternate with the recesses extending from said face to the aforesaid cavities, and screws having heads countersunk in said ears at the outer sides of the ears and having their shanks threaded into the body.

In testimony whereof, I sign the foregoing specification, this 27th day of August, 55 1920.

ARTHUR J. HOWE.
